UNITED STATES PATENT OFFICE

GEORGE HERBERT SCOTT AND FREDERICK MICHAEL ROPE, OF CARDINGTON, ENGLAND

AEROSTAT

Application filed December 15, 1927, Serial No. 240,320, and in Great Britain February 16, 1927.

This invention relates to aerostats and more particularly to automatic valves or valve systems for releasing gas when the pressure of gas in the gas bags has reached a predetermined limit, or when they are full and at a slight superpressure.

Hitherto, it has been the usual practice to fit gas valves at or near the bottom of the gas bags, the valves being maintained in a closed position by means of light springs or the like. The chief objections to the known arrangement are:—

(1) The valve floats up with the bottom of the gas bag when the bag is only partially full of gas.

(2) Owing to the small super-pressure at the bottom of the bag at which the valve has to operate, there is a difficulty in designing a valve to give a reasonable lift as compared with the diameter of the valve, so that in large gas bags valves of a very large diameter, or alternatively a large number of valves must be fitted, and chattering of the valve on its seating is liable to occur.

(3) A large area of opening is necessary to discharge any given volume of gas owing to the small super-pressure at the bottom of the bag available for driving the gas through the valve.

(4) It is difficult to adjust the light valve-closing spring to operate at the correct pressure under all conditions.

The present invention has for its object to overcome the above mentioned objections and to obtain other advantages.

According to one feature of the invention, an automatic gas valve for an aerostat gas bag is constructed and arranged so as to be approximately balanced as regards directly transmitted gas pressure from the gas bag, but so as to have a small resultant positive tendency to close. With this arrangement the pressure between the valve and its seating is proportional to the pressure in the gas bag for any pressure in the

gas bag lower than that at which the valve is designed to open. To the closing force due to the gas pressure an additional force independent of gas pressure may be provided, if desired, by a spring or other means.

According to another feature of the invention, a collapsible and expandible control chamber is provided for opening a gas valve for an aerostat gas bag in a decisive manner and to the full extent under predetermined conditions of pressure in the gas bag. The control chamber may be combined with the valve so as to minimize the number of moving parts.

According to another feature of the invention, the valve is arranged above the bottom of the gas bag and an operating pipe is provided for bringing about pressure in the control chamber, the pipe serving to connect the control chamber to the gas bag and being so arranged that the end of the pipe leading to the control chamber becomes charged with gas for opening the valve at a predetermined gas level or gas pressure in the gas bag.

According to another feature of the invention, one or more leaks are provided in the control chamber, or in the operating pipe, or a collapsible operating pipe or equivalent arrangement is used, to enable the pressure in the control chamber to fall and allow the automatic valve to close when the conditions causing it to open cease to exist.

According to another feature of the invention, a relay valve is used instead of or in association with the operating pipe for opening the valve at a predetermined pressure.

According to another feature of the invention, an auxiliary hand-operated valve is associated with the operating pipe, or with the control chamber and the gas bag for operating the automatic valve for manoeuvring or other purposes.

One arrangement of automatic gas valve the gas bag. The valve face F, which is attached to the outer diaphragm B and moves with the valve, sits upon a seating E constructed in the form of a cylinder and fixed in the gas bag aperture at X in any convenient gas-tight manner. A stiff diaphragm G of conical or conoidal form is fixed to the hub of the spider and is connected with the movable valve face F by means of a collapsible bellows H or equivalent means attached to said valve face. Normally, the movable valve cone nests near to the fixed diaphragm cone as shown. A chamber P is formed, bounded by the valve face F, the bellows H and the diaphragm G, and this chamber is open at Y to the pressure from the gas bag A, and a chamber J is formed, bounded by the diaphragm B, the bellows H and the diaphragm G, and this chamber is open at Z, Z', through the tubular guide M to the operating pipe C at the point L.

As shown, a gas bag A is fitted with a valve B in a position approximately at the horizontal diameter of the gas bag. It should be understood, however, that the valve position can be at the top or at any distance below the top of the gas bag, but is preferably above the highest level to which the bottom of the gas bag can rise during flight of the aerostat. The higher the valve position, the greater is the rate of discharge of the gas from the gas bag for any given size of valve. The valve is preferably placed so as to be readily accessible during flight.

A U-shaped operating or control pipe C communicates at one end with the gas bag at a point near the valve position, and at the other end with a control chamber J associated with the valve B. The looped part of the operating pipe is carried to a point at or near the bottom of the gas bag when full, or when full and at a slight super-pressure.

If this point is level with the bottom of the gas bag, the valve will operate as soon as the gas bag is full of gas. If on the other hand, as shown, the point, namely D, is situated at a vertical distance x below the bottom of the gas bag, the valve will operate when the super-pressure at the bottom of the gas bag is determined by the value of the distance x . By these means it is possible to regulate the super-pressure at which the valve will operate by altering the level of the point D.

A leak or vent indicated by the dotted lines at D' is provided at D, so that as soon as the super-pressure decreases below that due to the distance x of the point D below the bottom of the gas bag, air is permitted to enter the operating pipe and prevents siphonic action. Alternatively, the operating pipe C may be of such strength laterally as to collapse as soon as the super-pressure decreases below that due to the distance of the point D below the bottom of the gas bag, thereby preventing siphonic action.

The automatic valve proper preferably consists of an outer stiff diaphragm B having a conical or conoidal central portion and a cylindrical peripheral portion which carries a valve face F constructed in the form of an annular plate. The valve B', forming a part of the diaphragm B, is mounted at its centre on a tubular axial guide M which is supported at the centre or hub M' of a spider M' fixed in the aperture in the wall of

The movable valve face F is pressed upon the fixed valve seating E by the pressure from the gas bag in the chamber P, owing to their being superimposed on the valve face F (in addition to the balanced direct pressures from the gas bag acting on opposite sides of the valve face) the indirect pressure from the gas bag acting on the bellows and tending to expand them in the axial direction to close the valve. As shown, the outer diameter d' of the bellows is greater than the diameter d^2 of the valve seating, which is equal to the diameter of the connection between the bellows and the valve. The pressure of the movable valve face on the fixed seating is thus proportional to the pressure in the gas bag.

When pressure from the gas bag passes through the operating pipe C into the chamber J, owing to the bottom of the gas bag descending to the point D, the pressure operating on the central portion of the movable outer diaphragm B rapidly lifts the valve face F from the seating E to the full extent of the outward motion of the valve B' along the tubular guide M.

A small leak to the outer air may be provided at the highest point of the operating pipe, at L from the inside of the tubular guide M, or from the control chamber, so that when the operating pipe C ceases to supply gas to the chamber J owing to the bottom of the gas bag rising above the point D, the gas leaks away to the atmosphere, bringing the pressure in the chamber J back to atmospheric pressure.

A spring K, interposed between an abutment on the outer end of the tubular guide M and abutting the outer face of the valve B', then returns the valve face F on to the seating E, and as soon as contact takes place the closing pressure, due to the diameter d' being greater than the diameter d^2 as above mentioned, once more comes into action. Even

before the valve closes there is a tendency for it to close, apart from the action of the spring, owing to the average pressure on the outer side of the valve face F being greater than that on the inner side, due to the action of the jet of gas issuing from the gas bag through the opening Y.

A flared or funnel-shaped entrance N is fitted on the inner end of the cylindrical seating, to increase the coefficient of discharge of the valve. The funnel-shaped entrance has the effect of virtually increasing the diameter d^2 of the valve seating.

To facilitate the movement of the valve B' along the guide M, an axial ball cage S or a system of rollers is fitted between the guide and a tubular boss T at the centre of the valve.

The operation is as follows:—

Supposing the gas bag A to be half full of gas which is lighter than air, such gas will occupy the upper half of the bag and will have an approximately horizontal lower surface. If now the bag be progressively filled, the gas will enter the inner limb of the pipe C and will descend in this pipe as far as the level of the gas in the gas bag. As the filling of the bag with light gas proceeds, gas will eventually reach the point D of the pipe C. This will occur before the bag is full if the point D is placed above the level of the bottom of the bag. If, on the other hand, the point D be placed below the bottom of the bag, gas will reach the point D in the pipe C when the pressure at the bottom of the bag is equal to the difference of densities of air and gas multiplied by the vertical distance between the point D and the bottom of the bag, as indicated by α . When the gas does reach the point D, it will at once pass up the outer limb of the pipe C into the chamber J of the valve. In this chamber, the gas develops a pressure above the surrounding air which is rather less than the pressure of the gas at the same level in the bag, owing to the leak L, but is sufficient to open the valve by acting on the central portion of the movable outer diaphragm B in the manner hereinbefore described. If now the pressure at the bottom of the gas bag is reduced or the lower surface of the gas in the bag commences to rise, or both of these changes occur, the pressure of the gas at the point D in the pipe C will fall below that of the surrounding air. If the pipe C were rigid, gas would continue to flow through such pipe, maintaining a flow through the leak L and a pressure in the chamber J, but owing to the fact that the pipe C is either collapsible or is provided with the vent D' at D, as hereinbefore described, it will either collapse and thus prevent further flow of the gas or air will enter through the vent D' and thereby destroy siphonic action of the gas through the legs of the U-shaped pipe C into the chamber J of the valve, and the leaking off of the gas from the chamber

J through the vent L will cause the pressure in said chamber to drop to atmospheric and allow the valve to close in the manner hereinbefore described.

In another modification, the valve may be made to be operated by hand, whatever the degree of fullness of the gas bag, by fitting a small hand-operated cross connection valve O between the two legs of the operation pipe, or by equivalent means for obviating the necessity of fitting separate manœuvring valves in an airship.

Having thus described the nature of the said invention and the best means we know of carrying the same into practical effect, we claim:—

1. An automatic gas valve for an aerostat gas bag, comprising a valve face plate subject to the direct pressure of the gas bag on both faces, a seat for said face plate, and means actuated by the pressure of the gas bag operating to close the valve face plate.

2. An automatic gas valve for an aerostat gas bag comprising a valve face plate subject to the direct pressure of the gas bag on both faces, and a collapsible and expandible chamber communicating with the interior of the gas bag and attached at its free end to the valve face plate.

3. An automatic gas valve for an aerostat gas bag according to claim 1, having associated with it a collapsible and expandible control chamber, and a conduit capable of venting to the atmosphere and connecting said chamber with the interior of the gas bag.

4. An automatic gas valve for an aerostat gas bag according to claim 1, arranged above the bottom of the gas bag and having associated with it a collapsible and expandible control chamber, and a pipe serving to connect the control chamber with the gas bag and acting as an operating or siphon means, said pipe being provided with means to enable the pressure in the control chamber to fall and allow the valve face plate to close when the conditions causing it to open cease to exist.

5. An automatic gas valve for an aerostat gas bag according to claim 1, arranged above the bottom of the gas bag and associated with a collapsible and expandible control chamber, and a pipe serving to connect the control chamber with the gas bag and acting as an operating or siphon means, and an auxiliary hand-operated valve associated with said pipe.

6. An automatic gas valve for an aerostat gas bag according to claim 1, comprising a valve face plate in the form of an annular plate, a stationary stiff diaphragm, and a collapsible bellows connecting the said stationary diaphragm with the annular plate and thereby forming a chamber communicating with the interior of the gas bag.

7. An automatic gas valve for an aerostat gas bag according to claim 1, comprising a

valve face plate in the form of an annular plate, a stationary stiff diaphragm and a collapsible bellows connecting the said stationary diaphragm with the annular plate, an outer stiff and movable diaphragm also connected with the annular plate, said outer diaphragm enclosing said collapsible bellows, and a pipe connecting the interior of the gas bag with the chamber enclosed between the said outer diaphragm and the said bellows.

In testimony whereof we have signed our names to this specification.

GEORGE HERBERT SCOTT.
